UNITED STATES PATENT OFFICE.

OLAUS T. HODNEFIELD, OF LOS ANGELES, CALIFORNIA.

DESIGN FOR A RING.

Application filed August 14, 1922. Serial No. 3,385. Term of patent 3½ years.

To all whom it may concern:

Be it known that I, OLAUS T. HODNEFIELD, a citizen of the United States, residing at Los Angeles, in the county of Los Angeles and State of California, have invented a new, original, and ornamental Design for Ring, of which the following is a specification, references being had to the accompanying drawing, forming part thereof.

In the drawing, Fig. 1 is a plan view of a

ring embodying my new design. Fig. 2 is a side elevation of the ring corresponding to Fig. 1.

I claim:

The ornamental design for a ring, as shown.

OLAUS T. HODNEFIELD.
